PORTABLE BAR

Harlan W. Haaker, Omaha, Nebr.

Application May 12, 1938, Serial No. 207,461

1 Claim. (Cl. 206—4)

This invention relates generally to portable cases and particularly to portable bars embodied in a carrying case.

It is an important object of my invention to provide an improved receptacle or case for carrying and holding the necessary bar equipment for the preparation and serving of beverages of various kinds on camping trips, at home or the like.

10 It is another object of my invention to provide a device of this character wherein supplementary articles and accessories may be carried.

Another object of the invention is to provide 15 a device of this character adapted to be so opened that, when thus opened and in use, the articles therein are easily accessible.

Still another object of the invention is to provide 20 a device of this character having a compartment with an ice box therein.

A further object of the invention is to provide 25 a device of this character having means in the ice box compartment adapted to retain the ice box in an upstanding position in the case when same is in the normal open position for use.

A still further object of the invention is to provide 30 a device of this character wherein the articles contained therein are held securely against shifting or breaking when the case is in the closed position.

Numerous other objects and advantages of the invention will be apparent as it is better understood from the following detailed description, which, taken in connection with the accompanying drawing, discloses a preferred embodiment thereof.

Referring to the drawing:

Figure 1 is an end elevation of the invention 40 in an open position wherein one side of the case is in a vertical position.

Figure 2 is a front elevation of same showing the inside of the case.

Figure 3 is a side elevation of the opposite end 45 of the case with respect to the end shown in Figure 1 wherein the opposite side of the case is in a vertical position.

Figure 4 is a front elevation of same showing the inside of the case.

50 Figure 5 is an end elevation of the case in normal position for use.

Figure 6 is a partial section of the ice box compartment showing the grooves in the bottom and side thereof for reception of the front and 55 rear lower edges of the ice box to retain same

in an upright position when the case is in the normal position for use.

Referring more particularly to the drawing, which illustrates a preferred embodiment of the invention, the case comprises two sections or parts of substantially equal size and depth, each section having an outer side being respectively numbered 10 and 11. The first referred to section has end pieces 12 and 13, a bottom 14, and top 15 to which a handle 16 is secured. The other section includes ends 17 and 18, a bottom 19 and a top 20. The bottom pieces 14 and 19 of the respective sections of the case are secured together by hinges 21 and the open sides of the sections face each other.

One section of the case is divided into compartments by vertical partitions 22, 23, 24, 25, 26 and 27. Central compartment 23 is provided with a block 29 at the bottom thereof having a recess therein adapted to receive the bottom 20 portion of a Seltzer- or siphon-bottle 30 therein to prevent said bottle from shifting and breaking. Partition 25 is provided with a clip 31 within the upper portion of compartment 23 adapted to removably secure a recharging accessory 31a. 25 A cork-screw bottle-opener 32 is hung on a hook 33 screwed into partition 24 opposite clip 31. Other compartments formed by the partitions are adapted to receive a small liquor bottle 34, a bottle B for bourbon, a bottle R for rye, a 30 bottle G for gin, a bottle 35 for ginger ale or charged soda water, and another small liquor bottle 36, respectively. Above bottle 34 is a horizontal shelf which forms the bottom for a compartment for decks of cards 37; above bottle 35 B is a shelf which forms the bottom of a compartment for lemons or limes or the like numbered 38, a short front wall 39 preventing said fruit from slipping out of the compartment; and other horizontal shelves, above the bottles R, G 40 and 36 form compartments for towels 40, cigarettes 41 and card decks 42 respectively. A small compartment 43 for miscellaneous articles is provided above bottle 35.

The opposite section of the case is provided 45 with vertical partitions 44 to form the sides of an ice box compartment 45 in which is removably received an ice box 46, preferably of metal, having a cover 47 with a handle 48. The compartment 45 may be suitably insulated if desired and above the ice box 46 is a horizontal shelf 49 between the vertical partitions 44 which forms the bottom of a compartment 50 for gas cartridges for recharging the siphon-bottle. A low front wall 51 prevents the cartridges from 55

- sliding out of the compartment 50. Extending laterally from the vertical partitions 44 are horizontal shelves 52, vertically spaced from each other, having openings therein adapted to receive and hold glasses 53, and the lower shelves are provided with small openings therein adapted to receive the handles of stirring spoons 54, the depending ends of the handles of said spoons 54 resting on the bottom 19 of the case section.
- 10 The case is provided with latches 55 and a lock 56 for securing and locking same when closed. When said case is closed it comprises a compact receptacle which may be easily carried about, placed in an automobile trunk or the like, or stored away. It should be noted that when the case is in the closed position the horizontal shelves of one section are adapted to abut against the bottles of the other side to prevent them becoming displaced and broken.
- 15 In use the case is opened and placed on a suitable support in the position shown in Figure 5 wherein the lower outside edge 57 of each section or side rests on said support. A strap 58 limits the opening of the case so that the two sections or sides are at substantially a ninety degree (90°) angle with respect to each other and each side or section is at substantially a forty five degree (45°) angle with respect to the support on which the case rests.
- 20 The ice box 46 is adapted to be raised to the vertical position shown in Figures 5 and 6 and the lower edges thereof are longitudinally received in grooves 59 and 60 in the bottom 19 and side 11 respectively, said grooves being so positioned as to removably secure the ice box in a vertical position. The cover 47 of the box 46

may then be taken off for removal of ice cubes from said box 46.

All the ingredients for mixing various drinks are contained in the case as well as other accessories for parties and the like.

It is thought that the invention and many of its attendant advantages will be readily understood from the foregoing description and it will be apparent that various changes may be made in the form, construction, and arrangement of the parts without departing from the spirit and scope of the invention or sacrificing all of its material advantages, the form hereinbefore described being merely a preferred embodiment thereof.

Having thus described my invention what I claim and desire to secure by Letters Patent is:

A portable bar comprising a two sectioned case hinged together, said sections being of substantially equal depth and each having an open side, said open sides facing each other, means adapted to limit the opening of the case so that said case may be placed on a suitable flat horizontal surface with the outer lower side edges of each section resting on said surface when the case is open, said case having an ice-box compartment in one section thereof, and an ice-box removably received in said compartment, the bottom and side of said ice-box compartment having parallel grooves therein adapted to receive the front and rear lower edges of the ice-box for supporting same in an upright position when the case is opened and in position for use.
